(57) **CLAIM**

The ornamental design for an LED high bay light, as shown and described.

DESCRIPTION

FIG. 1 is a front view of an LED high bay light of the present invention.

FIG. 2 is a back view thereof.

FIG. 3 is a left view thereof.

FIG. 4 is a right view thereof.

FIG. 5 is a top view thereof.

FIG. 6 is a bottom view thereof.

FIG. 7 is a first perspective view thereof.

FIG. 8 is a second perspective view thereof; and,

FIG. 9 is a third perspective view thereof.

The broken lines represent portions of the LED high bay light and form no part of the claimed design.
